UNITED STATES PATENT OFFICE.

SHERWOOD E. EDWARDS, OF NEW ORLEANS, LOUISIANA.

GAME APPARATUS.

Application filed July 30, 1927. Serial No. 209,489.

The present invention is concerned with a game apparatus which may have a wide range of utility, but which is primarily intended for use in playing an indoor game of 5 marbles.

An object of the invention is to provide an apparatus of this character with which such a game of skill may be played, the apparatus rendering the game highly interesting and 10 amusing and permitting playing much in the manner of the ordinary outdoor game of marbles commonly played on the ground.

Objects of the invention are to provide a game apparatus of this character which will 15 be simple and practical in construction, rugged and durable in use, neat and attractive in appearance, well suited to the requirements of economical manufacture, and a collapsible apparatus which may be folded 20 into a comparatively small compass when not in use.

With the above noted and other objects in view, the invention consists in certain novel features of construction and combinations 25 and arrangements of parts, as will be more fully hereinafter set forth and pointed out in the claims. The invention may be more fully understood from the following description in connection with the accompanying 30 drawings, wherein—

Fig. 1 is a top plan view showing the apparatus of the present invention set up in condition for use.

Fig. 2 is a longitudinal sectional view 35 therethrough on the line 2—2 of Fig. 1.

Fig. 3 is an end view thereof.

Fig. 4 is an opposite end view.

Fig. 5 is a sectional detail on the line 5—5 of Fig. 1.

Fig. 6 is a perspective view showing the apparatus in its folded inoperative position.

In the drawings I have used the reference numeral 10 to designate an upper playing board or field over which marbles are adapted to be hand propelled in the customary manner by a player, and a lower board 11 which provides an inclined gravitational return for the marbles.

Preferably, each of the boards 10 and 11 are formed of comparatively light thin stock, are of elongated formation, and provided with side rails 12 and 13 which prevent the marbles from rolling off the sides of either board.

Preferably, the upper board is slightly shorter than the lower one, and is hinged at

one end as by pins 14 to metal plates or brackets 15 secured to the outer faces of the rails 13 at one end of the latter. Board 10 is cut away at one end as indicated at 16 60 terminating short of the ends of the rails 12, so that marbles propelled from one end of the board 10 will drop off of the other end thereof and roll back to the player down the board 11 where they are stopped by a cross 65 rail 17 at the free end of the board.

The free end of the board 17 is supported upon suitable pads or feet 17^a and the other end thereof is maintained in elevated position by an easel 18. 70

The easel 18 is in the nature of a flat plate which in inoperative position overlies the face of the upper board 16 between the ends of the rails 12. Preferably, the same pins 14 which hingedly connect the rails 12 to the 75 brackets 15 provide pivots or trunnions for the easel 18, so that the latter may be swung through approximately 270° about its pivot from the position of Fig. 6 to the position of Fig. 2. In this latter position one edge 80 of the easel rests upon the floor and the other edge of the easel serves as a back-board or stop to block rapidly moving marbles passing over the edge of the upper board and direct them on to the lower return 85 board.

When the member 18 is in the position of Fig. 2, it may be retained against pivotal movement by swinging a pivoted latch member 19 into engagement with a keeper recess 90 formed in the ends of the lower rails 13.

With the parts in the position of Fig. 2, the board 11 is inclined, and the board 10 may be maintained in substantially horizontal position by a pair of props 21. These 95 props are pivoted as at 22 to the outer faces of the rails 12 near the free edge of the board 10, and include bifurcated free ends 23 engageable with studs 24 projecting laterally from the outer faces of the rails 13. 100

The boards 10 and 11 as above suggested are made of any suitable material, the upper board preferably being covered with a sheet of felt 25 or similar material which will deaden the noise of the marbles as well as 105 offer enough frictional resistance to prevent unduly rapid rolling thereof.

Preferably, a circle 26 is delineated on the board 10 near the hinged edge thereof. The players put an equal number of object 110 marbles in the circle and take turns shooting at them from the free edge of the board

10. The object is of course to knock the marbles out of the circle and off of the board 10, and cause the displaced object marbles and the shooter or taw to return down the 5 lower board. Suitable penalties may be imposed for causing either a shooter or object marble to escape from the confines of the apparatus by jumping over the easel or the rails of the board.

10 Obviously various changes and alterations might be made in the general form and arrangement of the parts described without departing from the invention. Hence I do not wish to limit myself to the details set 15 forth, but shall consider myself at liberty to make such changes and alterations as fairly fall within the spirit and scope of the appended claims.

I claim:

20 1. A game apparatus of the class described including a board constituting a playing field over which marbles are adapted to be rolled, a second board arranged thereunder constituting an inclined marble-returning 25 runway, said boards being pivotally connected together at one end, means for spacing the boards apart at their other end, an easel for elevating the hinged end of the lower board whereby the upper board may 30 be maintained in substantially horizontal position, the upper board at its hinged end terminating short of the lower one, whereby marbles rolling off of the upper board drop on to the lower one and are returned to the 35 shooter, said easel constituting a stop for blocking the marbles which roll off of the upper board and directing them on to the lower board.

2. A game apparatus of the class described including a board constituting a playing 40 field over which marbles are adapted to be rolled, a second board arranged thereunder constituting an inclined marble-returning runway, said boards being pivotally connected together at one end, means for spacing the boards apart at their other end, an easel for elevating the hinged end of the lower board, whereby the upper board may be maintained in substantially horizontal position, the upper board at its hinged end 45 terminating short of the lower one, whereby marbles rolling off of the upper board drop on to the lower one and are returned to the shooter, the upper board having a ring delineated thereon in which object marbles are 50 adapted to be placed.

3. A game apparatus including a pair of boards hingedly connected together at one end, an easel for supporting the hinged ends of the boards, means for supporting the free end of the upper board in spaced relation to the free floor-engaging end of the lower board, whereby the upper board may be maintained in approximately horizontal position, the upper board being cut away near 60 its hinged end whereby marbles rolling off the edge thereof will drop on to the inclined lower board and be returned to the shooter, means for locking the easel in board supporting position, the upper end of the easel 65 constituting a back stop and directing marbles on to the lower board.

Signed at New Orleans in the parish of Orleans and State of Louisiana this 25 day of July A. D. 1927.

SHERWOOD E. EDWARDS.
